CENTERLESS GRINDING MACHINE

Arthur Scrivener, Birmingham, England

Application January 2, 1948, Serial No. 194
In Great Britain September 28, 1946

2 Claims. (Cl. 51—103)

1

This invention has reference to improvements in or connected with centreless grinding machines, more particularly that type of machine in which the grinding wheel is associated with the control wheel for the positioning of the workpiece, and the object of the present invention is to avoid damage to the ends of the workpiece caused by skidding or slipping of the workpiece in relation to the grinding wheel during the feeding-in or feeding-out traverse of the workpiece so as to ensure an accurate co-ordination between the control wheel, grinding wheel and the workpiece.

The invention consists of the provision in centreless grinding machines of lead-in and/or lead-out rolls for the control of the workpiece relative to the grinding wheel, said rolls being freely mounted in contiguity with the periphery of the grinding wheel and located substantially within the width of the control wheel for the purpose set forth.

One means of carrying the present invention into practice as applied to the feeding or traversing of a workpiece through the gap normally obtaining between the periphery of the grinding wheel and the periphery of the control wheel is illustrated by the accompanying drawings, in which—

Fig. 1 is an end elevation of part of a centreless grinding machine showing the embodiment thereon of the subject-matter of the present invention.

Fig. 2 is a front elevation of the mechanism seen in Fig. 1 looking on the control wheel.

Fig. 3 is a detail view showing a modification in the form of the idle roller.

Referring first more particularly to Figs. 1 and 2 of the drawings, there is located on either side of the grinding wheel *a* a small idle roller *b* the axes whereof are in alignment, and the effective part of the peripheries whereof are located in substantial alignment with the active face-line of the grinding wheel disposed between the pair of idle rollers *b*.

Desirably the idle rollers are spring-urged in the direction of the control wheel *c* and this is effected by freely mounting each of the idle rollers at the lower end of dependent arms *d* clamped to a spindle *e*. Secured to the spindle *e* is a laterally extending arm *f* which co-operates with a set-screw *g* adjustably mounted in the frame *h* of the machine, the set-screw serving to limit the motion of the arm *d* when the workpiece *j* is withdrawn.

The arm *d* is flexibly anchored to the frame of the machine by means of a coiled tension

2

spring *k* which is adjustably connected by means of an eye bolt *l* the shank whereof passes through a boss in the frame *h* of the machine.

The control wheel *c* is preferably arranged so that the width is substantially equal to the width of the two idle rollers *b* plus the width of the grinding wheel *a*. By this means when the workpiece *j* is introduced between the control wheel and the grinding wheel the lead-in end of the workpiece is seized between the spring-urged lead-in roller and the periphery of the control wheel and is fed thereby to the grinding wheel without damage to the lead-in edge of the workpiece; likewise at the termination of the grinding operation the trailing end of the workpiece is led out between the other spring-urged roller and the control wheel so as to prevent damage to the trailing end of the workpiece upon the completion of the grinding operation.

Referring now more particularly to Fig. 3 of the drawings which illustrates a modification in the form of the idle roller *b* where it may be desired to govern the feed of a workpiece upon which it is required to produce a screw-thread by grinding, each idle roller would be formed with an annular tooth *b*¹, the tooth having a configuration conforming to that of the tooth to be ground on the workpiece by means of the grinding wheel so that by longitudinally adjusting the setting of the spring-urged rollers relative to the grinding wheel *a* the pitch of the teeth can be co-ordinated with the pitch of the teeth of the grinding wheel to ensure accurate positioning and co-ordination of the workpiece to the grinding wheel during the rotational traverse of the workpiece across the face of the grinding wheel in adjacency to the control wheel.

In Fig. 3 of the drawings it will be observed that the idle roller *b* which carries the tooth *b*¹ is mounted on the spindle *d*¹ laterally extending from the free end of the arm *d* by means of a collar *d*² and a headed set screw *d*³ located within a recess in the idle roller *b*, any required adjustment of the spindle *d*¹ being effected by means of the two nuts *d*⁴ mounted on either side of the arm *d*.

I claim:

1. In a centreless thread grinding machine having a thread grinding wheel and a control wheel mounted upon parallel spaced axes, the control wheel being movable transversely toward and away from the grinding wheel and having a surface extending axially beyond both sides of the grinding wheel, a pair of coaxial work support rollers, a raised, annular, circumferen-

tially extending tooth-shaped flange on the periphery of at least one of said rollers, and means for rotatably mounting said rollers with their axis parallel to the axis of said grinding wheel and adjustable axially thereof whereby the tooth-shaped flange is movable to accommodate different pitch teeth being ground on a work piece.

2. In a centreless grinder according to claim 1 in which the roller mounting means comprises a pair of parallel arms resiliently urged toward said control wheel, a mounting spindle on the end of each of said arms and roller bearings axially adjustably mounted on each of said spindles.

A. SCRIVENER.
